DISPENSING CONTAINER

Douglas C. Clarke, Mountain Lakes, N. J., assignor of one-third to Robert Ostertag, Brooklyn, N. Y.

Application August 30, 1945, Serial No. 613,530

3 Claims. (Cl. 206—42)

1

This invention relates to dispensing containers and particularly to dispensing containers of the sliding cover type.

The dispensing of pills and like articles is much simplified not only for injured and handicapped persons but also for able persons by the use of a container which permits a limited quantity of pills, for instance a single pill, to be dispensed while the remainder of the contents of the container is securely held therein. Many suggestions have been made by me and others for such containers but prior to the present invention the problems of the efficient use of the interior space in a container, of constructing a container simply and effectively, and of providing a container which can be easily packed, used, and operated, have never been satisfactorily solved. Pursuant to the present invention, on the other hand, there may be provided containers which have space for the inclusion of sets of directions or advertising matter, articles which will assist in the administration or use of the contents, material which is adapted to be utilized therewith, premiums or the like; which are operable with the utmost ease and effectiveness; which can be properly packed with the utmost ease; and which are sturdy and simple of construction and adapted to be constructed of any of a variety of materials.

The invention accordingly comprises the features of construction, combinations of elements, and arrangement of parts which will be exemplified in the constructions hereinafter set forth and the scope of the application of which will be indicated in the claims.

For a fuller understanding of the nature and objects of the invention reference should be had to the following detailed description taken in connection with the accompanying drawing, in which:

Figure 1 is a top perspective view of the body member of one form of container constructed in accordance with the invention;

Fig. 2 is a longitudinal sectional view along the line 2—2 of Fig. 1;

Fig. 3 is a perspective view of the complete container with the sliding cover in closed position;

Fig. 4 is a similar view with the sliding cover in open position;

Fig. 5 is a transverse sectional view along the line 5—5 of Fig. 4;

Fig. 6 is a vertical sectional view along the line 6—6 of Fig. 3;

Fig. 7 is a similar view along the line 7—7 of Fig. 4;

2

Fig. 8 is a fragmentary view similar to Fig. 4 illustrating a modified form of construction;

Fig. 9 is a view similar to Fig. 3 illustrating another modification; and

Fig. 10 is a view similar to Fig. 9 showing the cover in open position.

In the embodiment of the invention exemplified in Figs. 1-7 there is provided a shallow rectangular body member 5 formed of sheet metal, plastic or other suitable material to provide side portions 6 and transversely extending barrier means 7, 8 and 9 which set off the interior of the body member to provide a main compartment 10 normally communicating with a dispensing compartment 11 and to provide also an additional compartment 12 which for practical purposes is entirely separated from the other two compartments. The longitudinal sides of the body portion are turned outwardly as at 13 to retain the flanges 14 of a cover member 15 so that relative sliding movement of the cover member on the body member is permitted. The cover member is formed near one end with a longitudinally extending barrier element 16 and, as will be seen in Figs. 1 and 4, the barrier members 7 and 8 are separated to provide a channel 17 for the movement of the barrier member 16, although, if the barrier members 7, 8 and 16 are less than half the height of the container, this may be omitted. In the present instance, the distance between the barrier member 8 and the parallel side portion of the body member 11 which is nearest thereto and the distance between the barrier member 8 and the barrier member 9 is substantially the same. The length of the barrier member 16 is of similar extent although, as will be appreciated, the type of contents will determine the necessary length of the barrier member 16. For instance, if pills 20 of the size shown in Figs. 6 and 7 are employed, the barrier member 16 will need to be only a fraction of its exemplified length to prevent the escape of additional pills when the cover is open. As exemplified, the cover is formed with indentations 21 which serve to stop the cover when it has moved a distance equal to the distance between the barrier members 8 and 9, but it will be understood that these may be placed differently depending on the type of contents to be used. It is, however, important that they function at a time when the longitudinal barrier member carried by the cover still serves wholly or partially to prevent movement of an article to be dispensed from the main compartment 10 to the dispensing compartment 11 whenever the cover

is in open position. The cover is likewise formed with an opening 22 through which a pill 20 or other article, or in certain instances a plurality of smaller articles, may be dispensed from the dispensing compartment whenever the cover is in open position. When the cover is in closed position the barrier lies in the compartment 12 and the opening 22 lies above it. Desirably, the compartment 12 may contain an advertising circular 23 or other article or articles. One or more minor barrier means as shown at 24 for example is provided to prevent such article from sliding into the path of movement of the barrier member 16. The latter may in some instances be made of such small depth as to clear a circular, however. The provision of this compartment fills a long-felt need in sliding-cover dispensing containers since it has been difficult if not impossible to provide directions and/or advertising literature with most of these due to the relative inaccessibility of those portions of the container which would normally be used to retain such literature. It likewise serves to contain articles which are adapted to be used in conjunction with or in the application of an article dispensed by the container.

As will be seen, a series of articles such as the pills 20 may be laid in the main compartment and dispensing compartment as shown in Fig. 6. Movement of the cover to the position of Fig. 7 brings the barrier means 16 into position where it will prevent additional pills from moving into the space occupied by the single pill to be dispensed and will at the same time bring the opening 22 above the latter pill so that it will be readily tipped out of the compartment. The same movement of the cover will permit the circular such as 23 containing directions or advertising matter to be removed and read or another article to be removed and used. It is easy, moreover, to put the circular or the other article or articles back into the compartment 12. When the cover is again moved to closed position communication between the dispensing compartment and the main compartment is again reestablished and another pill 20 may take its place in the dispensing compartment ready for use whenever the cover is again slid to open position.

As will be appreciated, the illustrated construction may be modified in various ways without departing from the spirit and scope of the invention in its broader aspects. For example, instead of a cut-out opening 22 a cover member such as 15b of Fig. 8 may be cut away at one corner to provide a recessed portion 22b, and instead of the barrier means 16 being formed by a fold this barrier means may be provided by a bent-over uncutaway portion shown at 16b.

A lateral rather than an upper opening may be provided. An arrangement of this sort is shown in Figs. 9 and 10. In this case the side of the body member is cut away for a short distance to provide an opening 25 at one side of the dispensing compartment and the cover 15c is formed with a portion 26 adapted to lie over this opening when the cover is in closed position, but to move away from it when the cover is slid to open position. In the present instance, the portion 26 is a part of one of two sides 14c which are bent over at the bottom as shown at 29 so as to replace the flanges 14. For the sake of symmetry the two flanges 14c are extended the same distance to the left (Fig. 10).

What is claimed is:

1. A dispensing container comprising a shallow body member and a sliding cover member, barrier means on the body member defining two sides of a dispensing compartment a third side of which is provided by one of the first two mentioned members, means including part of the aforesaid barrier means providing an additional compartment, and barrier means on the cover member adapted to be in the additional compartment when the cover member is closed and to cooperate with the barrier means on the body member when the cover member is open to prevent movement of articles between said dispensing compartment and the remainder of the body member, said cover member being formed with an opening which permits dispensing from said dispensing compartment when said cover member is in the last mentioned position.
2. A dispensing container comprising a shallow generally rectangular body member, a sliding cover member, barrier means on the body member at positions spaced from three sides of the body member and extending transversely to the direction of movement of the cover member and defining two sides of a dispensing compartment, other barrier means cooperating with one of the aforesaid barrier means and with certain side portions of the body member to define an additional compartment, and barrier means on the cover member extending in the direction of movement of the cover member adapted to separate said dispensing compartment from the interior of said body member when the cover member is open but to permit communication of said dispensing compartment with the interior of the body member when the cover member is closed, said cover member being recessed to permit communication between said dispensing compartment and the exterior of said container when said cover member is open.
3. A dispensing container comprising a shallow generally rectangular body member and a sliding cover member, spaced barrier means on the body member extending transversely to the direction of movement of the cover member but only for a portion of the lateral extent of the body member, said barrier means defining two sides of a dispensing compartment a third side of which is provided by one of the first two mentioned members, and barrier means on the cover member extending in the direction of movement of the cover member and adapted to provide the fourth side of said dispensing compartment when said cover is in a dispensing position and to be elsewhere when said cover is in a retaining position, the top of said cover being cut away to permit egress of articles from the dispensing compartment when said cover is in a dispensing position.
